FIG. 1 is a front view of a hair processing accelerator in accordance with my new design;
FIG. 2 is a back view thereof;
FIG. 3 is a left side view thereof;
FIG. 4 is a right side view thereof;
FIG. 5 is a top plan view thereof;
FIG. 6 is a bottom view thereof;
FIG. 7 is a rear perspective view thereof;
FIG. 8 is a front perspective view thereof;
FIG. 9 is a right side elevation with the head of a person and a stand shown in phantom outline;
FIG. 10 is a front view of the hair processing accelerator shown in an alternate position; and,
FIG. 11 is a front view of the hair processing accelerator in another alternate position.

The broken lines showing a stand and the head of a person in FIG. 9 are for illustrative purposes only and do not form part of the claimed design.
